IRRIGATION VALVE

Carl E. Holm, Livermore, Calif., assignor to FMC Corporation, San Jose, Calif., a corporation of Delaware

Filed July 23, 1968, Ser. No. 12,856

Term of patent 14 years

Int. Cl. D23—01

U.S. Cl. 23—19

FIG. 1

FIG. 2

FIGURE 1 is a front perspective view of an irrigation valve embodying my new design; and

FIGURE 2 is a rear perspective view thereof.

The fragmentary broken line showing of a supply pipe in FIGURES 1 and 2 is for purposes of illustration only.

I claim:

The ornamental design for an irrigation valve, as shown and described.
